UNITED STATES PATENT OFFICE

CHARLES W. MACKAY, OF TULSA, OKLAHOMA, ASSIGNOR TO THE TEXAS COMPANY, OF NEW YORK, N. Y., A CORPORATION OF DELAWARE

TREATMENT OF HYDROCARBON OILS

Application filed May 19, 1930. Serial No. 453,463.

This invention is concerned with the art of cracking hydrocarbon oils and has particular reference to certain novel and useful methods of withdrawing and handling the products of reaction, such as tar or residue, from cracking vessels.

Considerable difficulty has been experienced in withdrawing tar or residue from cracking stills due particularly to the formation of coke deposits in the lines through which it is sought to withdraw the residue. In accordance with my invention the products of reaction, as withdrawn from a cracking vessel, are maintained in movement or circulation in such a way as to keep any coke or carbon particles in suspension to thus facilitate the removal of the residue from the system and prevent the plugging up of lines.

The difficulties that have been encountered with respect to coke formations have been especially aggravating when it has been sought to pass the tar or residue directly to an expansion chamber, such as for auto-distillation, since any expansion that may take place in lines or chambers is accompanied with a vaporizing action tending to result in the deposition of coke or carbon, and to overcome these difficulties my invention has in view particularly the provision of circulating the tar or residue at points where expansion or reduction in pressure may take place.

The invention can best be explained by reference to a specific apparatus constituting an example of the invention and in order to more fully set forth the invention reference will now be had to the accompanying drawing which is a diagrammatic sectional elevation of an apparatus constructed in accordance with the invention and constituting an embodiment thereof.

In the apparatus thus illustrated a plurality of cracking stills 10 are indicated. It is to be understood that the invention is capable of being practiced in connection with a single cracking chamber or with any number of cracking chambers operated either in combination as a single unit or as separate and distinct units. Draw-off lines 11 are shown extending from the stills 10 to a common header or tar line 12 which is provided with a pres-

sure reducing valve 13 and communicates with a vessel 14 which may function as a surge or cushion drum. A draw-off line 15 extends from the surge drum 14 to a pump 16 provided with a discharge line 17 which connects with the surge drum so that the contents of the drum may be continuously maintained in circulation by the pump 16, drawing off liquid from the drum 14 through the line 15 and returning it to the drum through the line 17. The line 17 is connected to a line 18 having a control valve 19 for the purpose of permitting the withdrawal of a regulated quantity of the liquid in circulation through the surge drum 14 and for delivering the liquid thus withdrawn to a stripping still 20. The stripping still is shown provided with a residue draw-off line 21 and a vapor line 22 which extends to a dephlegmator or fractionating tower 23. A vapor line 24 leads to a condenser 25 and a receiving drum 26 is provided for collecting the condensate. A line 27 is provided for withdrawing reflux condensate from the tower 23.

In practicing the invention with the apparatus illustrated the oil is subjected to cracking temperatures under superatmospheric pressure in the stills 10. When distillation is carried on in the stills 10 the vapors are removed through means not shown and a residue is developed in the stills which is withdrawn through the lines 11 to the tar header 12. The drum 14 is operated at pressures intermediate those obtaining in the stills 10 and the stripping still 20, the pressure being reduced in the drum 14 by the valve 13 and the pressure being reduced in the still 20 by the valve 19. The surge drum may serve to act as a cushion to absorb or take care of variations in pressure that may occur due to the taking of shots or drags from the stills 10 through the lines 11 and to facilitate the even delivery of a regulated amount of material to the stripping still 20, so that pressure fluctuations therein may be reduced to a minimum and an even distillation obtained. It is to be understood that the relative pressures obtaining in the stills 10, surge drum 14, and stripping still 20 may be varied within comparatively wide limits but as an example

of the invention it may be stated that with the stills 10 operating under about 400 pounds pressure, the pressure in the surge drum 14 may fluctuate, for instance, between 75 to 250 5 pounds pressure with an average pressure of about 200 pounds, and the pressure in the stripping still 20 may, for example, be approximately atmospheric or slightly higher.

The residue withdrawn from the stills 10 10 is thus expanded into the surge drum 14 and the pump 16 takes suction on the contents of the drum and pumps the material back through the line 17 to thus maintain the contents of the drum in constant movement or 15 circulation so that any coke formed is held in suspension in the flowing oil. A regulated quantity of liquid is permitted to be withdrawn through the line 18 and valve 19 into the stripping still 20. Distillation in the 20 still 20 is carried on to the extent desired, which distillation may be aided by steam or other carrier gas or heating means, if necessary. Thus the material delivered to the 25 still 20 may be distilled down to a fuel oil residuum or to a pitch, which may be withdrawn in a heated condition through the line 21, or the distillation may be carried on to the extent of coking the residue. The 30 evolved vapors are passed to the fractionating tower 23 which separates out a light vapor fraction which after being condensed in the coil 25 is collected in the receiver 26. This condensate may, for example, be a gasoline distillate. The reflux condensate 35 formed in the tower 23 may be withdrawn through the line 27 and may be conducted to a cracking apparatus for further cracking or otherwise utilized.

In a modification of the invention, in lieu 40 of the surge drum 14, a drum may be provided which is connected, not only to the tar header 12, but also to vapor lines in communication with the stills 10, so that this 45 drum may be held under approximately the pressure obtaining in the cracking stills. Due to the maintenance of still pressure on this drum some "post-cracking" may take place in the drum and some cooling may take place. But as the cooling which may take 50 place occurs while under approximately the pressure of the stills the tendency toward the formation of coke is minimized, while the circulation of the contents of the drum, which is accomplished in a similar manner 55 to the circulation carried on in the drum 14, which has been specifically described, further prevents any clogging up of lines through

which the residue withdrawn from the cracking stills is being delivered to the stripping still 20.

Obviously many modifications and variations of the invention, as hereinbefore set forth, may be made without departing from the spirit and scope thereof, and therefore, only such limitations should be imposed as are indicated in the appended claims.

I claim:

1. In the conversion of higher boiling hydrocarbon oils into lower boiling ones wherein the oil is subjected to cracking temperatures in a chamber under superatmospheric pressure, the process that comprises withdrawing liquid from the cracking chamber, reducing the pressure on the withdrawn liquid and delivering it into a surge chamber from which no separate vapor fraction is withdrawn and which is maintained at lower pressure than that of the cracking chamber, continuously withdrawing liquid from the surge chamber and passing it back to said chamber to thus create and maintain a circulation of the liquid delivered to said chamber, withdrawing from the liquid thus in circulation a regulated quantity of liquid and directing it into a stripping still wherein distillation is carried on at lower pressure than that of the surge chamber.

2. In the conversion of higher boiling hydrocarbon oils into lower boiling ones wherein a residue developed in the cracking of the oil under superatmospheric pressure is removed from the cracking still and passed to a low pressure zone for autogenous distillation, the process that comprises withdrawing the residue from the cracking still in a confined stream and delivering the residue, before it is passed to the low pressure auto-distillation zone, to an enlarged chamber from which no separate vapor fraction is withdrawn and wherein a body of the residue is collected and maintained under a fluctuating pressure intermediate that of the cracking still and the auto-distillation zone, continuously withdrawing liquid from said enlarged chamber and passing it back to said chamber to thus establish and maintain a constant circulation of the liquid tending to maintain coke particles in suspension therein and withdrawing from the liquid thus in cyclic movement a regulated quantity thereof and directing the liquid thus withdrawn to the auto-distillation zone.

CHARLES W. MACKAY.
